UNITED STATES PATENT OFFICE.

ANTHONY J. STOUGES, OF QUEENS VILLAGE, NEW YORK, ASSIGNOR TO MERGEN-
THALER LINOTYPE COMPANY, A CORPORATION OF NEW YORK.

TYPOGRAPHICAL DISTRIBUTING MECHANISM.

Application filed March 2, 1927. Serial No. 171,930.

This invention relates to typographical distributing machines, such as linotype machines of the general organization represented in U. S. Letters Patent to O. Mergenthaler, No. 436,582, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In these machines, the composed lines, after casting, are carried upward by a so-called second elevator and transferred into a distributor box, where the matrices are separated from one another by means of a reciprocating finger which lifts them successively into the threads of the overlying distributor screws. It has been found in practice that occasionally, and under certain conditions hereinafter pointed out, a matrix will slip off the finger as it is being lifted and become jammed in the distributor, causing damage to itself or other parts and resulting in the stoppage of the distributor with the attendant annoyances and delays.

The present invention is intended to overcome these difficulties and contemplates an automatic device which will act to maintain the individual matrices in proper engagement with the finger as they are being lifted into the screws. In the embodiment illustrated, the proposed device is in the form of a horizontally disposed guide plate resiliently mounted in the distributor box and provided at one end with an inclined or beveled surface arranged to cooperate with the lower projecting ear of each matrix as it is raised by the lifting finger.

In the accompanying drawings, the invention has been shown merely in preferred form and by way of example and obviously many changes and variations may be made therein which will still be comprised within its spirit. It is to be understood, therefore, that the invention is not limited to any specific form or embodiment except in so far as such limitations are specified in the claims.

Referring to the drawings:

Fig. 1 is a side elevation of a distributor

box having the present improvements applied thereto:

Fig. 2 is a similar view, with parts broken away, showing the lifting finger in its upper position;

Fig. 3 is a fragmentary perspective view illustrating the constructional details of the proposed device and the manner in which it is attached to the distributor box; and

Fig. 4 is a view similar to Fig. 2 illustrating the damage that might occur to a matrix in the event of its becoming disengaged from the lifting finger as it is being lifted into the screws.

The well-known type of distributing mechanism shown in Fig. 1 includes the distributor proper, which comprises the distributor bar A and the associated set of matrix conveying screws A¹, the distributor box B supported at the receiving end of the distributor and formed with front and rear side walls B¹, B², and the vertically reciprocating finger C, the latter being pivoted to the free end of the rocking lever C¹ and actuated by the cam A² secured to the end of one of the distributor screw spindles. After casting, the line of matrices is transported to the top of the machine and shifted horizontally by the spring-actuated transfer slide or pusher D through the box B and up against the arresting shoulders B³ formed on the upper and lower guide rails B⁴. The matrices are then detached from the line by the reciprocating finger C, which engages them by their bottom edges as they are pushed ahead by the slide D and lifts them, one after another, above the shoulders B³ into the overlying conveying screws A¹.

It is the practice to limit the purchase of the finger C on the bottom edges of the matrices to about .027", or in any event the thickness of the thinnest matrix, so that only one matrix may be lifted at a time, the influence of the pusher D, in pressing the matrices squarely up against the arresting shoulders B³, serving to brace or guide them facewise and thus prevent them from slipping off the finger C. Ordinarily, i. e., when the machine is being operated at normal speed, the pusher is not retracted to transfer a succeeding line until the last matrix of the preceding line has been fed to the screws. It frequently happens, however, that when the machine is operating at full capacity, the

first matrix line will not have been completely distributed when the pusher recedes, one or more matrices remaining in the box. Under such conditions, the undistributed 5 matrix or matrices, being temporarily deprived of the facewise support of the pusher D, are likely to be jarred off the lifting finger C by the normal vibrations of the machine or actually pulled therefrom by the pusher 10 itself if the matrices happen to be dirty or gummed up. As a result, said matrices in falling may become lodged in the distributor box B and are very likely to become wedged and bent out of shape between the 15 shoulders B³ and the threads of the distributor screws. An accident of this kind is depicted in Fig. 4.

It is the object of the present invention to obviate the foregoing difficulties, and to this 20 end auxiliary means are provided for maintaining the individual matrices, when unsupported by the pusher D, in engagement with the finger C as they are being lifted into the screws. In the present instance, such means 25 consist of a horizontally disposed guide plate E slidably attached for slight endwise movement to the side wall B¹ of the distributor box B and arranged to cooperate with the lower projecting ear x of each leading matrix 30 when engaged with the lifting finger C. In the normal position of the guide plate E, its vertical edge E¹ will stand spaced from the arresting shoulders B³ a horizontal distance determined by the thickness of the thinnest matrix ears, so that when a thin 35 matrix is being lifted above the shoulders it will just about clear the edge E¹ and yet be restrained thereby from slipping off the lifting finger C until it is picked up by the 40 screws. However, in order that the plate E may be capable of adapting itself to matrices of greater thicknesses and of cooperating therewith in the same manner, it is further formed with an inclined or beveled surface 45 E² merging with the vertical edge E¹ at its lower end. As best shown in Fig. 3, the guide plate is supported in place by means of a screw E³ and a screw stud E⁴ which are slidably arranged in horizontal elongated slots b cut through the side wall B¹ of 50 the distributor box. A spring F, anchored at one end to a fixed eye F¹ and connected at its other end to the stud E⁴, tends to hold the guide plate constantly in its normal or 55 foremost position, the screws E³, E⁴ banking against the ends of their respective slots b.

According to the foregoing arrangement, any matrix which happens to occupy a position 60 against the arresting shoulders B³, when the pusher D has receded, may be lifted into the distributor screws by the finger C without danger of becoming disengaged therefrom, the customary lip c of the lifting finger serving to support the matrix against 65 facewise displacement in one direction and

the guide plate E serving to maintain it at such time against facewise displacement in the other direction. If the matrix be one of the thicker variety, its thicker lower ear x in rising will engage the beveled surface 70 E² of the guide plate and cam the plate back against the tension of the spring F until it passes onto the vertical edge E¹, which thereafter maintains it in engagement with the lifting finger. These thicker matrices 75 are thus really clamped to the finger C until the screws pick them up, although the tension of the spring F should be very light and only strong enough to impart the desired resiliency to the plate E. 80

While the invention has been herein shown in preferred form, it is obvious that the guide plate E might be applied in the form of a lever instead of a slide, which lever could be pivoted to the box B in such manner as to locate the matrix engaging surfaces in the required positions. These and other modifications will readily suggest themselves to those skilled in the art. 85

Having thus described my invention, its 90 construction and mode of operation, what I claim and desire to secure by Letters Patent of the United States is as follows:

1. In a typographical distributing mechanism comprising a distributor bar and a set 95 of matrix conveying screws, the combination of a reciprocating finger for lifting the matrices one after another into the screws, means for presenting the matrices successively to the finger, and auxiliary means 100 for holding the individual matrices irrespective of thickness against rearward displacement from the finger as they are being lifted.

2. In a typographical distributing mechanism comprising a distributor bar and a set of matrix conveying screws, the combination of a reciprocating finger for lifting the matrices one after another into the screws, a retractable pusher for presenting 110 the matrices successively to the finger, and auxiliary means for holding the individual matrices irrespective of thickness against rearward displacement from the lifting finger when the pusher is retracted. 115

3. In a typographical distributing mechanism comprising a distributor bar and a set of matrix conveying screws, the combination of a reciprocating finger for lifting the matrices one after another into the screws, 120 means for presenting the matrices successively to the finger, and means arranged to cooperate with the individual matrices while supported on the finger for maintaining them in proper engagement therewith as 125 they are being lifted.

4. In a typographical distributing mechanism comprising a distributor bar and a set of matrix conveying screws, the combination of a distributor box, a reciprocating 130

finger associated therewith for lifting the matrices one after another into the screws, means for presenting the matrices successively to the finger, and a yieldable guide member mounted in the box and arranged to cooperate with the projecting ears of the individual matrices for holding them irrespective of thickness against rearward displacement from the finger as they are being 10 lifted.

5. In a typographical distributing mechanism comprising a distributor bar and a set of matrix conveying screws, the combination of a distributor box, a reciprocating finger associated therewith for lifting the matrices one after another into the screws, and a guide member for holding the individual matrices irrespective of thickness against rearward displacement from the finger as they are lifted, the said guide member being resiliently mounted in the box and formed with a beveled surface to cooperate with matrices of different thicknesses.

20 6. In a typographical distributing mechanism of the class described, the combination of matrix supporting rails formed with arresting shoulders, a reciprocating finger for lifting the matrices successively above said shoulders, and a horizontally disposed guide plate for maintaining the individual matrices in engagement with the finger as they are lifted, said guide plate having a vertical matrix engaging edge normally spaced from the arresting shoulders a horizontal distance determined by the thickness of the thinnest matrix.

25 7. In a typographical distributing mechanism comprising a distributor bar and a set

of matrix conveying screws, the combination 40 of matrix supporting rails formed with arresting shoulders, a reciprocating finger for lifting the matrices successively above said shoulders into the screws, and a spring-actuated horizontally disposed guide plate 45 arranged to cooperate with the lower projecting ears of the individual matrices for maintaining them in proper position on the finger as they are lifted, said guide plate having a vertical forward edge normally 50 spaced from the arresting shoulders a horizontal distance determined by the thickness of the thinnest matrix, and having further an inclined or beveled surface at the lower end of said vertical edge to adapt the plate 55 to matrix ears of different thicknesses.

8. The distributor box B provided with matrix sustaining rails B⁴ formed with the arresting shoulders B³, the lipped matrix lifting finger C, and the matrix guide plate 60 E having the vertical edge E' spaced at a given horizontal distance from the arresting shoulders B³, said guide plate being arranged to hold the individual matrices irrespective of thickness against rearward displacement from the lifting finger C as they are being lifted.

9. The distributor box B provided with matrix sustaining rails B⁴ formed with the arresting shoulders B³, the lipped matrix lifting finger C, the matrix guide plate E 70 having the vertical edge E' spaced at a given horizontal distance from the arresting shoulders B³, and the beveled surface E² merging into the vertical edge E'. 75

In testimony whereof, I have affixed my signature hereto.

ANTHONY J. STOUGES. [L.S.]
